LUGGAGE CASE

Andreas Christen, Zurich, Switzerland, assignor to
"Swissair" Schweizerische Luftverkehr-Aktiengesellschaft, Zurich Switzerland

Filed Jan. 16, 1967, Ser. No. 5,427

Claims priority, application Switzerland July 18, 1966

Term of patent 7 years

(Cl. D87—5)

FIG.1

The bottom of the luggage case is substantially plain and unornamented.

I claim:

The ornamental design for a luggage case, substantially as shown and described.
